(57) **CLAIM**

The ornamental design for an inkjet printer, substantially as shown and described.

DESCRIPTION

FIG. 1 is a perspective view of an inkjet printer in accordance with the present invention, shown with the fold-up media supply tray in an operable position for printing; FIG. 2 is a top plan view thereof; FIG. 3 is a front elevational view thereof; FIG. 4 is a bottom plan view thereof; FIG. 5 is a rear elevational view thereof; FIG. 6 is a left side elevational view thereof; and, FIG. 7 is a right side elevational view thereof. The broken lines in FIGS. 1-3, 5 and 7, are for illustrative purposes only and form no part of the claimed design.
